CLAIM

The ornamental design for an augmented reality console, as shown and described.

DESCRIPTION

FIG. 1 is a top perspective view of a new design for an augmented reality console.

FIG. 2 is a top view of a new design for an augmented reality console.

FIG. 3 is a left side view of a new design for an augmented reality console.

FIG. 4 is a right side view of a new design for an augmented reality console.

FIG. 5 is a front view of a new design for an augmented reality console.

FIG. 6 is a rear view of a new design for an augmented reality console.

FIG. 7 is a bottom view of a new design for an augmented reality console.

FIG. 8 is a top perspective disassembled view of a new design for an augmented reality console; and,

FIG. 9 is a bottom perspective disassembled view of a new design for an augmented reality console.

The broken lines in the drawings depict portions of the augmented reality console that form no part of the claimed design.
